UNITED STATES PATENT OFFICE.

JOHN E. SEYMOUR, OF ORANGE, NEW JERSEY, ASSIGNOR OF ONE-HALF
TO WINFIELD S. WARDELL, OF ORANGE, NEW JERSEY.

PIPE-VISE.

No. 838,143.

Specification of Letters Patent.

Patented Dec. 11, 1906.

Application filed May 23, 1905. Serial No. 261,765.

To all whom it may concern:

Be it known that I, JOHN E. SEYMOUR, a citizen of the United States, residing at Orange, in the county of Essex and State of New Jersey, have invented certain new and useful Improvements in Pipe-Vises; and I do hereby declare the following to be a full, clear, and exact description of the invention, such as will enable others skilled in the art to 10 which it appertains to make and use the same, reference being had to the accompanying drawings, and to numerals of reference marked thereon, which form a part of this specification.

15 This invention relates more particularly to certain improvements in that class of pipe-vises illustrated by the vises shown and described in Patent No. 601,313 and Patent No. 618,846, granted to George F. Condit in 20 the years 1897 and 1898, respectively, the objects of the present improvements being to facilitate the operation of inserting the pipe into and removing it from the vise and to secure other advantages and results, some of 25 which may be hereinafter referred to in connection with the description of the working parts.

30 The invention consists in the improved pipe-vise and in the arrangements and combinations of parts of the same, all substantially as will be hereinafter set forth and finally embraced in the clauses of the claim.

Referring to the accompanying drawings, in which like numerals of reference indicate 35 corresponding parts in each of the several figures, Figure 1 is a front view of my improved pipe-vise. Fig. 2 is a section of the same, taken at line x. Fig. 3 is a side view of said vise. Fig. 4 is a detail side view of a 40 certain gripping-jaw and its carrier. Figs. 5 and 6 are detail sectional views showing the female parts for engaging the vise-screw and serving in facilitating the work of gripping and releasing the pipe. Figs. 7 and 8 are 45 sectional views illustrating the arrangement of a certain sectional nut and showing the screw in position. Fig. 9 is a detail plan of a certain collar, and Fig. 10 is a detail showing the parts engaging the pipe.

50 In said drawings, 10 indicates the base of the frame of the machine, having oppositely-inclined bearings 11, forming a V-shaped recess in which the pipe may rest, as indicated by the dotted outlines in Fig. 1. 12 indi-

cates the screw-carrying upper portion of the 55 said frame, which is hinged or pivoted at 13 and fastened to the lower section by the latch or link 14 in any suitable manner, the said latch or link being adapted to release said upper part to enable it to be turned upward or 60 opened to permit the outpassage of the pipe with facility.

Between the downwardly-extending arms 15 15 of the upper portion, which provide vertical slideways 16, is a carrier 17 for gripping-jaws 18 18, which latter are suspended from the said carrier by means of a suspensory pin 19, extending horizontally through a tubular extension 20 of said carrier. Said jaws project downward from bearings 21 on 70 the under side of the carrier to the inclined bearings 11 and when in engagement with said inclined bearings are directed toward one another and into holding contact with the pipe as said jaws are forced downward. 75 Said jaws are forced apart at their free ends as the same are raised from the pipe by means of springs 22, arranged in the said tubular extension on the horizontal rod 19, which projects oppositely from the ends of 80 the tube into perforations at the upper ends of the jaws, the said jaws being suspended from said rod and free to swing thereon to a limited extent of movement.

At the upper side of the carrier 17 is a 85 socket adapted to receive the ball end of the screw 25, by means of which the carrier and its jaws 18 are forced into clamping relation to the pipe. Said screw is longitudinally grooved to enable said screw to be moved by 90 a direct longitudinal movement toward and from the pipe, so as to quickly apply the jaws to said pipe and withdraw the same therefrom without the delay occasioned by the usual screwing and unscrewing process. 95 With this end in view I form at the center of the top of the arching upper portion 12 a box-like formation 26, which is interiorly threaded, as at 27, at its lower part to engage with the threads of the screw 25, and above said threaded portion is recessed or chambered to receive a nut 28, the said nut being exteriorly threaded, as at 29, to engage threads formed on the walls of the annular chamber or recess in the said box-like 100 formation. The said nut 28 is also threaded interiorly to engage the screw 25. The continuity of the thread of the screw 25 is broken 105

2
by longitudinally grooving the said screw, as indicated at 30 in Figs. 1 and 7, and the female threads 27 and the interior of the nut 28 are similarly grooved, and thus on the male member 25 four (more or less, if desired) threaded longitudinal ribs are formed, and on the female members four corresponding vertical grooves are formed, and so when the vertical grooves of the box formation and the vertical grooves of the nut 28 are in correspondence, as in Fig. 6, and the longitudinal threaded ribs are in coincidence with the said corresponding grooves then there will be no intermeshing of the screw-threads and the screw 25 can be moved directly lengthwise; but by turning the nut a quarter-turn, more or less, and thus bringing the vertical grooves of the female nut to positions vertically out of correspondence with the grooves of the box-like formation, as indicated in Fig. 5, then such longitudinal movement of the screw 25 is prevented, and said screw may be turned effectively by means of the handle 31 to force the jaws 18 into clamping relation to 25 the pipe.

To hold the nut 28 in its position for screwing, I prefer to employ a spring-latch 34, adapted to slide vertically in a recess 35, formed in the box-like formation 26 at one side of the recess for the nut 28, said recess 35 containing at its bottom a spring 36, on which the latch is seated and normally held in its catching position to engage the nut. Said latch is provided with a finger-piece 37, by means of which it can be conveniently pressed out of catching relation with the nut. Said enlargement 26 at a little distance from said latch is provided with an upwardly-projecting fixed pin 38, which serves to limit the turning movement of the nut. Said nut 28 is provided with laterally-projecting lugs 39 39, (shown more clearly in Figs. 5 and 6,) between which the fixed pin 38 extends, and the movement of the nut is limited by said pin 38 to an extent about equal to the space between said lugs. When the nut is at the limit of one of its movements, the interior grooves of said nut and the box-like formation are in coincidence, as in Fig. 6. When 50 at the limit of its reverse movement, said grooves are out of coincidence, as in Fig. 5, so as to prevent a direct longitudinal movement of the screw 25. In this latter position the latch, forced by the spring 36, passes automatically into engagement with one of the lugs and locks the nut to prevent turning. The nut may be turned by hand by means of a finger-piece 40, projecting laterally out therefrom. I prefer also to employ means 55 for automatically turning said nut, and to this end I employ a collar 41, which is held down upon the top face of the nut 28 with some considerable pressure by means of a spring 42, coiled around a reduced portion 60 of said collar and bearing down on a flange

43 thereof. The upper end of said springs bears against the under side of a cap 44, secured to the nut and adapted to protect the spring. The reduced upper end of the collar 41 extends between the cap 44 and screw 25, as shown in Fig. 8, and said collar is free to move up against the tension of the spring 42. On the under side of said collar are tapered projections 44^a. These are disposed on opposite sides of the axial center of the collar 41 and project downward into recesses 45 of substantially the same shape, formed in the upper side or face of the nut 28, so as to clutch therewith. On the interior walls of said collar 41 are ribs or keys 46, fitting within the grooves 30 of the screw 25, and thus the said collar is compelled to turn with the screw, but is free to slide lengthwise of said screw.

On turning the screw 25, by means of the handle 31, to release the jaws 18 from the pipe the collar 41 is immediately turned, and because of the relation of the inclined projections to the recessed nut the said collar is also turned to bring the grooves of the nut 28 and formation 26 into vertical coincidence, thus enabling the screw to be at once raised without continued turning. On reversing the movement of the handle 31 the collar throws the nut back to the position in which the grooves are out of coincidence, and on further turning the screw the projection 44^a is free to ride up the incline of the recess 45, so that the screwing operation is not materially interfered with.

To bring the clutching-jaws 18 into proper clutching relation as well with small pipes as with large, the teeth at and near the lower ends of the said jaws are disposed at the inner sides of said jaws, as shown in Fig. 10, where the three or four teeth near the extremity of each jaw are formed in the segment of a circle, such as 50, while those farther away from said circle are arranged in a straight line 51, and thus in practice I am enabled to hold pipes of a great variety of sizes securely and with firmness.

The collar 41 and nut 28 may together be considered to be a sectional nut operating together to effect the results before detailed.

Having thus described the invention, what I claim as new is—

1. The improved press or clutch herein described, comprising means for supporting the parts to be pressed or clutched, means for supporting a nut, said nut disposed above the first said supporting means, and a screw arranged in said nut, said nut and screw being each vertically grooved and adapted to permit a direct vertical movement of said screw in the direction of the axis of said screw and threaded means for closing the grooves to enable the screw to be normally operated.

2. In a clutch, the combination with the frame, screw and carrier operated by said

screw, and having an extension to receive jaw-operating springs, of clutching-jaws bearing underneath said carrier, a horizontal rod supporting said jaws and springs arranged on said rod and bearing oppositely on said jaws.

3. A vise comprising a fixed jaw and a movable jaw, the fixed jaw having a screw-threaded perforation with longitudinal grooves, a screw-threaded bolt having longitudinal grooves therein, in the perforation of the fixed jaw, and a nut on the fixed jaw arranged to partially rotate thereon and having grooves arranged to be thrown in and out of register with the grooves in the fixed jaw.

4. A vise comprising a fixed jaw, a mov-

able jaw, the fixed jaw having a grooved screw-threaded perforation, a grooved screw-threaded bolt in the perforation to actuate the movable jaw, a nut rotatable on the fixed jaw and embracing the bolt, the said nut having grooves arranged to be thrown in and out of register with the grooves in the fixed jaw, and means to limit the rotation of the nut.

In testimony that I claim the foregoing I have hereunto set my hand this 13th day of May, 1905.

JOHN E. SEYMOUR.
